UNITED STATES PATENT OFFICE.

PAUL ABRAHAM, OF NEW YORK, N. Y.

SIGNAL-LANTERN.

SPECIFICATION forming part of Letters Patent No. 733,892, dated July 14, 1903.

Application filed November 21, 1902. Serial No. 132,248. (No model.)

To all whom it may concern:

Be it known that I, PAUL ABRAHAM, a subject of the Emperor of Germany, and a resident of the city and State of New York, have 5 invented certain new and useful Improvements in Signal-Lanterns, of which the following is a specification.

This invention relates to signal-lanterns; and its primary object is to facilitate changing the color of the light given by the lantern, especially when the lantern is intended to exhibit one color of light at one side and a different color at another side.

Other objects will hereinafter appear.

15 In the accompanying drawings, Figure 1 is a side elevation of a lantern embodying my improvements. Fig. 2 is a sectional elevation taken on the line 2 of Fig. 3. Fig. 3 is a sectional plan illustrating the body of the lantern and the slides and operating-levers mounted therein. Fig. 4 is a sectional plan illustrating a modified form of the slide-actuating lever. Fig. 5 is a vertical section of a portion of the lantern, illustrating particularly the relation of the colored or white glass panes, the sashes in which they are secured, and the frames in which the sashes slide up and down. Fig. 6 illustrates the connection of the finger-keys to the sash-operating levers 30 and the manner in which the latter are mounted within the casing of the lantern. Fig. 7 is a perspective fragmentary view of the upper portion of the device illustrated at Fig. 4. Fig. 8 illustrates how one of the arms fixed 35 upon the outer sash may be bent around the frame in which the inner sash slides. Fig. 9 illustrates one of the finger-keys held in working position by means of a detent.

In the several views like parts are designated by like characters of reference.

The body 10 of the lantern contains, as usual, a lamp 11, held by catches 12, and near its bottom is provided with lenses 13 and 14 at right angles to each other for the usual purpose. Between the lens 13 and the lamp are disposed one or more vertical glass panes 15 45 16, which are mounted in sashes 17 18, one behind the other and independently movable to a position of use or disuse. Each sash 50 may consist of a lower channel-bar A for the reception of the lower edge of the pane, an upper parallel bar B, between the portions

whereof the pane may be inserted, and connecting side bars C. At one side these sashes may be guided between vertical strips 19, 20, 55 and 21, the two latter being preferably parts of a channel-bar, as shown, and all three being fixed to the inner side of the lantern-body and extending substantially from the top to the bottom of the lantern. At the other side 60 said sashes may be guided between fixed vertical strips 22, 23, and 24. The sashes may, however, work in other suitable frames or guideways, or they may be otherwise guided from a position of use to one of disuse. Between the other lens 14 and the lamp are also provided glass panes 25 26, mounted in sashes 27 28, the latter working between guide-strips 29, 30, and 31 upon one side, the last two forming a channel-bar, as shown, and strips 70 32, 33, and 34 upon the other side. The group of strips 22, 23, 24, 32, 33, and 34 may be in the form of a single bracket secured to the inside of the lantern, as shown, and the same is true of each of the other groups of strips 75 shown.

By preference the sash 17 is united to the sash 27 by means of upper and lower tie-bars 35, and the two sashes are thus made into a single frame and may move up and down as 80 a single piece, thereby to change the lights exhibited by both of the lenses 13 and 14. The sashes 18 and 28 are likewise united by tie-bars 36, forming the two inner sashes into 85 a single frame. Thus the two inner panes may be moved together up or down as well as the two outer frames. It will be seen that the sashes composing each frame are at right angles to each other. By this construction and arrangement the changing of the lights 90 exhibited at the two sides of the lantern is facilitated. If desired, one or more similar frames may be added.

For convenience of operating the inner frame I fix arms 37 to the upper bar B of each 95 of the sashes, said arms being parallel to each other, but projecting at an angle of forty-five degrees from said bars B. Slots 38 in said arms are engaged by pins 39, provided upon tines 40 of a forked lever 41, said pins being 100 axially coincident and said lever being forked, so as to clear the lamp and being fulcrumed by means of a pivot-pin 42 upon a bracket 43, fixed within the lantern. By rocking this

lever the double sash is slid up or down, the slots 38 permitting the necessary play of the pins 39. For the same purpose the outer frame is provided with slotted arms 44, which at 45 are bent around the fixed vertical guides 21 and 31 and secured to the upper ends of the sashes. The slotted arms 44 may be engaged by pins 46, provided upon the free ends of levers 47, also fulcrumed by means of the pin 42. Said levers may be fast to said pin 42, and the latter may turn freely in the bracket and in the hole in the lever 41. Preferably the lever 40 41 is nested within the arms 47, as shown at Fig. 3, thereby contributing to economy of space. By operating the arms 47 the outer double sash 27 17 may be lifted or depressed. The levers may be operated in any suitable way, preferably by keys 48 49, mounted upon the tips of vertical sliding stems 50 51, which work in guides provided upon a portion 10^a of the lantern-body, Fig. 9. At its lower end the key-stem 50 has a pin-and-slot connection 52 with the sash-operating lever 41, while the lower end of the stem 51 is branched or forked and provided with pin-and-slot connections 53 to the levers 47, the latter operating as one piece. Said key-stems, it will be observed, are connected to the short arms of the levers, which are levers of the first order by preference, the sashes being operated in a downward direction, preferably by gravity, and being lifted downward by pressure upon the finger-keys.

Any suitable means may be provided for maintaining either or both of the double sashes in the elevated position of disuse; but by preference I employ latches 54 55, adapted to catch over the heads of the depressed keys, Figs. 2 and 9, said latches being mounted upon the outside of the lantern and controlled by a suitable spring or springs 56 and being also provided with releasing-arms 57.

Having thus described my invention, what I claim as new, and desire to secure by Letters Patent of the United States, is as follows:

1. A signal-lantern for railroad use, comprising a body, individual openings distinct one from another upon different sides of the body, and a plurality of sashes behind each opening; each sash being operatively connected to one of the sashes at a different opening so as to be movable therewith to a position of use or disuse; and means for guiding the connected sashes in their movements; so that by moving one set of sashes to a position of disuse and another set to a position of use, changes of signals may be effected equal in number to the number of sashes in a set.

2. A signal-lantern for railroad use, comprising a body, individual openings distinct one from another upon different sides of the body, a plurality of sashes behind each opening, each sash being operatively connected to one of the sashes at a different opening so as to be movable therewith to a position of use or disuse; means for guiding the connected sashes in their movements; and differently-

colored glasses respectively mounted in the connected sashes.

3. A signal-lantern for railroad use, comprising a body, individual openings distinct one from another upon different sides of the body, a lens at each opening, said lenses being wholly independent one of another so that one may show a light of one color while another is showing a light of a different color, a plurality of frames mounted behind said lenses, one frame behind the other, and each frame consisting of sashes arranged angularly with reference one to another; said frames being independently movable up and down; and means for guiding said frames in their up and down movements.

4. A signal-lantern for railroad use, comprising a body, individual openings distinct one from another upon different sides of the body, a plurality of frames, each comprising a plurality of sashes, one behind each opening, a plurality of levers, one for each frame, releasable detaining means for said levers, means independent of said levers for guiding said frames in up and down movements, and differently-colored glasses respectively mounted in the several sashes composing each frame.

5. A signal-lantern for railroad use, comprising a body, individual openings distinct from one another upon adjacent sides of the body, a lens at each opening, said lenses being mounted at right angles to one another, a plurality of frames behind the lenses, each frame comprising sashes mounted at right angles to each other, vertical guides for said frames, means for operating one frame independently of another, and differently-colored glasses respectively mounted in the several sashes composing each frame.

6. A signal-lantern for railroad use, comprising a body having lenses at an angle to each other, a sash behind each lens, said sashes being rigidly connected, a second sash behind each lens, said second sashes being also rigidly connected, a finger-lever connected to the first sashes to move them together, and a finger-lever connected to the second sashes, to move them together independently of the first sashes.

7. A signal-lantern for railroad use, comprising a body having individual openings distinct from one another upon different sides of the body, a frame behind said openings and composed of angularly-arranged sashes each having a differently-colored glass, a second frame behind the first and composed of angularly-arranged sashes having glasses colored differently from the glasses in the first-mentioned frame, levers of the first order having pin-and-slot connections with said frames, means independent of said levers for guiding said frames up and down, and finger-keys having stems guided in the framework and having pin-and-slot connections with said levers.

8. A signal-lantern comprising a body, a

lamp therein, sashes mounted for up-and-down movement and arranged at an angle to each other and positively connected, arms on said sashes, a lever forked and connected at its forks to said arms, a finger-piece; and differently-colored glasses respectively mounted in said sashes; said lantern having openings at corresponding sides, so as to display simultaneously differently-colored lights in different directions.

9. A signal-lantern comprising a body, a lamp therein, a plurality of sets of sashes, the sashes in each set being guided for independent up-and-down movement relatively to the other set, arms on each set of sashes, levers having arms connected to each of said sash-arms, and keys connected to said levers; and differently-colored glasses respectively mounted in said sashes; said lantern having

openings at corresponding sides, so as to display simultaneously differently-colored lights in different directions.

10. A signal-lantern for railroad use, comprising a body, individual openings distinct one from another upon different sides of the body, and a plurality of sashes behind each opening; each sash being open at the top for the insertion of glasses, and being operatively connected to one of the sashes at a different opening in the body of the lantern, so as to be movable with said connected sash to a position of use or disuse; and means for guiding the connected sashes in their movements.

PAUL ABRAHAM.
